Christie LLP(57) **CLAIM**

The ornamental design for outlet wall organizer, as shown and described.

DESCRIPTION

FIG. 1 is perspective view of an outlet wall organizer design; FIG. 2 is a front view thereof; and, FIG. 3 is a right side view which is a mirror image of the left side view thereof.
The broken line showing immediately adjacent the shaded areas represents boundaries to the claimed design and forms no part of the claimed design.

1 Claim, 3 Drawing Sheets(56)
